UNITED STATES PATENT OFFICE

CHARLES BRYAN WAGNER, OF SPRING MILLS, PENNSYLVANIA

POLE LADDER

Application filed June 23, 1930. Serial No. 463,179.

This invention relates to new and useful improvements in pole ladders particularly for use on telephone, telegraph and electric poles, but it is to be understood that a ladder in accordance with this invention may be utilized for any purpose for which the same is found adapted and desirable.

An important feature of the invention resides in the provision of a housing or casing which is permanently mounted on the pole having pivotally mounted for swinging movement therein a series of steps which are operatively connected together in a manner to permit the same to be simultaneously swung to operative or inoperative position.

Another important feature of the invention resides in the provision of resilient means for automatically returning the steps to inoperative position within the housing where the same are out of the way.

Other objects of the invention are to provide a pole ladder of the aforementioned character which will be simple in construction, strong, durable, efficient in its use and which may be manufactured at comparatively low cost.

All of the foregoing and still further objects and advantages of the invention may become apparent from a study of the following specification, taken in connection with the accompanying drawings wherein like characters of reference designate corresponding parts throughout the several views, and wherein:—

Figure 1 is a view in side elevation showing a ladder constructed in accordance with this invention mounted in position on the pole with the steps in inoperative position within the housing or casing.

Figure 2 is a view in side elevation of the device with the steps swung outwardly to operative position.

Figure 3 is a detail view in elevation showing the ladder removed from the housing.

Figure 4 is a fragmentary sectional view

on an enlarged scale showing one of the steps in inoperative or retracted position in the housing and means for securing the same therein.

Figure 5 is a fragmentary detail view in section showing one of the steps in operative position.

Referring to the drawings in detail, it will be seen that the reference numeral 1 designates a pole upon the upper end portion of which is mounted a cross arm 2 which is braced by the members 3. A housing 4 of substantially U-shaped horizontal cross section is rigidly secured longitudinally on the pole 1 by the bolts 5.

A series of steps 6 are pivotally mounted for swinging movement in vertically spaced relation on the transversely extending pins 7 in the housing or casing 4, said pins 7 extending vertically through the hub portion 8 formed integrally on the said steps 6. The steps 6 are provided with upturned free end portions 9 to prevent slipping therefrom. The hub portion 8 of each step 6 has formed therein an angular recess which is indicated to advantage in broken lines in Figure 5 of the drawings, said recess providing furcations 10 between which extends the operating rod 11 which is pivotally connected to the furcations as at 12. The inner walls of the recess which forms the furcations 10 is of right angular formation, as indicated at 13 and the angles of said walls are adapted for abutting engagement with the adjacent sides of the operating rod 11 when the steps 6 are in operative or inoperative position. In this manner the outward swinging movement of the steps 6 is limited in a manner to maintain said steps in a horizontal position.

At its lower end portion the housing or casing 4 is provided with a partition wall 14 having a polygonal opening through which slidably extends the threaded shank 15 having a nut 16 threaded for adjustment on its lower end portion for supporting a washer 90

17. At its upper end the shank 15 is forked and pivotally connected to the rod 11 as at 18. A coiled spring 19 encircles the shank 15 and has one end engaged on the washer 17 and its upper end engaged with the partition 14 in a manner to yieldingly urge the shank 15 and the rod 11 downwardly.

10 A hook 20 is loosely mounted for swinging movement on the lower portion of the casing or housing 4 and is engageable with the apertured ear 21 on the free end portion of the lowermost step for retaining said step in extended or operative position against the tension of the coiled spring 19. Formed integrally on the free edges of the housing 4 are the apertured ears 22 for the passage of a removable pin 22' for providing positive means for retaining the steps in inoperative or retracted position in the casing or housing, said pin 22' being engageable with one of the steps as clearly seen in Figure 4 of the drawings.

15 As will be readily apparent, when it is desired to use the ladder the pin 22' is removed and when one of the steps is swung outwardly to horizontal position the movement is transmitted to all of the steps through the rod 11. The hook 20 is then engaged in the ear 21 and the steps are thus maintained in horizontal position. When through using the ladder, the hook 20 is disengaged from the apertured ear 21 and the coil spring 19 will move the shank 15 and the rod 11 downwardly and thus swing the 20 steps upwardly to a position within the housing or casing 4. The pin 22' is then reinserted in the apertured ears and the steps are thus positively secured in retracted position and out of the way.

25 40 It is believed that the many advantages of a pole ladder constructed in accordance with this invention will be readily understood, and although the preferred embodiment of the invention is as illustrated and described, it 45 is to be understood that changes in the details of construction may be had which will fall within the scope of the invention as claimed.

What is claimed is:—

50 1. A pole ladder of the character described comprising an elongated housing of substantially U-shaped cross section mounted longitudinally on the pole, a series of steps pivotally mounted in vertically spaced relation for 55 swinging movement into and out of the housing, an elongated rod pivotally connected to each of the steps and constituting means for operatively connecting said steps together for simultaneous operation, and resilient means 60 operatively engaged with the rod in a manner to yieldingly urge the same in a direction to move the steps to inoperative position within the housing.

65 2. A pole ladder of the character described comprising an elongated housing open at its

front and adapted to be mounted vertically on the pole, a series of steps pivotally mounted in vertically spaced relation for swinging movement into and out of the housing, said steps having one end portion slotted in a manner to provide furcations, an elongated rod extending through the slots and pivotally connected to the furcations, said rods constituting means for swinging the steps to both operative and inoperative position, certain of the walls of the slots engageable with the elongated rod in a manner to limit the swinging movement of the steps and maintain the same in a substantially horizontal position when swung outwardly from the housing. 70 80

3. A pole ladder of the character described comprising an elongated housing open at its front and adapted to be mounted vertically on the pole, a series of steps pivotally mounted in vertically spaced relation for swinging movement into and out of the housing, said steps having one end portion slotted in a manner to provide furcations, an elongated rod extending through the slots and pivotally connected to the furcations, said rods constituting means for swinging the steps to both operative and inoperative position, certain of the walls of the slots engageable with the elongated rod in a manner to limit the swinging movement of the steps and maintain the same in a substantially horizontal position when swung outwardly from the housing, means mounted on the housing for releasably securing the steps in operative position, means mounted on the housing for releasably maintaining the steps in inoperative position, and resilient means operatively coupled to the rod for yieldingly urging said rod in a direction to move the steps to inoperative position in the housing. 85 90 100

4. A pole ladder of the character described comprising an elongated housing open at its front and adapted to be mounted vertically on the pole, a series of steps pivotally mounted in vertically spaced relation for swinging movement into and out of the housing, said steps having one end portion slotted in a manner to provide furcations, an elongated rod extending through the slots and pivotally connected to the furcations, said rods constituting means for swinging the steps to both operative and inoperative position, certain of the walls of the slots engageable with the elongated rod in a manner to limit the swinging movement of the steps and maintain the same in a substantially horizontal position when swung outwardly from the housing, means mounted on the housing for releasably securing the steps in operative position, means mounted on the housing for releasably maintaining the steps in inoperative position, and resilient means operatively coupled to the rod for yieldingly urging said rod in a direction to move the steps to inoperative position in the housing, said means 110 115 120 125 130

comprising a partition formed integrally in the lower end portion of the housing, said partition having an opening therethrough, a threaded shank connected to the lower end portion of the elongated rod and extending slidably through the opening in the partition, a washer mounted for adjustment on the shank in opposed relation to the partition, and a coil spring mounted on the shank and engaged with the washer and the partition.

In testimony whereof I affix my signature.
CHARLES BRYAN WAGNER.
